Primary Examiner — Melanie H Tung*Assistant Examiner* — Bao-Yen Nguyen(74) *Attorney, Agent, or Firm* — Fishman Stewart PLLC(57) **CLAIM**

The ornamental design for an aerosol container, as shown and described.

DESCRIPTION

1. Aerosol container

1.1 is a perspective view.

1.2 is a back view.

1.3 is a top view.

1.4 is a bottom view.

The front, right, and left views of the design are identical to the back view. The broken lines shown in the drawings illustrate portions of the aerosol container that form no part of the claimed design.
